[57] CLAIM

The ornamental design for a cup, as shown and described.

DESCRIPTION

FIG. 1 is a perspective view of a cup showing my new design;

FIG. 2 is a side elevational view thereof, the side not shown being a mirror image of the side shown;

FIG. 3 a side elevational view as seen from the left side of FIG. 2;

FIG. 4 is side elevational view as seen from the right side of FIG. 2;

FIG. 5 is a top plan view thereof;

FIG. 6 is bottom view thereof; and

FIG. 7 is a side elevational view of an alternate embodiment, with the top and bottom of the alternate embodiment being identical to the first embodiment as illustrated in FIGS. 5 and 6; and,

FIG. 8 is a perspective view of the alternate embodiment of the cup as illustrated in FIG. 7.

1 Claim, 7 Drawing Sheets
